UNITED STATES PATENT OFFICE.

ROY B. OLDER, OF DANVILLE, ILLINOIS, ASSIGNOR TO ALLITH PROUTY COMPANY, OF DANVILLE, ILLINOIS, A CORPORATION OF ILLINOIS.

BRACKET.

1,307,413.

Specification of Letters Patent. Patented June 24, 1919.

Application filed June 2, 1917. Serial No. 172,379.

To all whom it may concern:

Be it known that I, ROY B. OLDER, a citizen of the United States, residing at Danville, in the county of Vermilion and State 5 of Illinois, have invented certain new and useful Improvements in Brackets, of which the following is a specification.

My invention refers to means for adjustably supporting tracks or the like for use in 10 mounting garage or other sliding doors where it is desirable to apply the track at an inclination to the opening on which mounted or to accommodate it to unevenness of the doorway.

15 Experience has shown that oftentimes, because of certain building construction, it is necessary to incline the door supporting track to the doorway to avoid certain obstructions and also for making a tight 20 closure of the door and for permitting the door to stand away from the doorway when open. This is particularly true when sliding doors are installed in garages of limited width so that it is necessary to employ ac- 25 cordion folding doors or large doors adapted to move around the inside corners of the building. In such installations it is necessary to adjust the tracks at an angle or on a curve so as to provide proper clearance 30 for the folding doors also for the large rolling doors.

One of the objects of my invention is to provide a device which may be readily attached to any head room and means co-oper- 35 ating with the attaching member for supporting the track in adjusted positions.

Another object is to provide an attaching member for a track supporting element which is so connected to the supporting 40 bracket as to permit pivotal movement of the track supporting member with respect to the bracket.

A further object is to provide an adjustable track supporting bracket having 45 means for positive engagement between the attaching member and the track supporting member.

50 A still further object is to provide a bracket for supporting the track at an incline to a door opening having a track supporting member which is pivotally mounted with respect to the attaching member and the provision of means for locking the track supporting member against re-

tative movement after it has been adjusted 55 to proper rotative position.

A still further object is to provide a bracket for supporting a track or the like in which the load or track supporting member is rotatably and bodily movably associated with the body portion of said bracket.

The device embodying my invention comprises substantially a body member having a wall attaching portion, an extending body portion and a track engaging portion, the 65 track engaging portion being associated with the extending portion in such a manner as to be bodily movable thereon, the extending portion preferably being provided with a series of serrations to engage a serrated 70 member carried by the track supporting section for positive engagement at any portion of the length of the extending portion, also means for locking the track engaging 75 section in engagement with the extending portion.

These and other objects will be apparent from an observation of the drawings, wherein—

Figure 1 is a vertical sectional view 80 through the preferred embodiment of my device, and

Fig. 2 is an elevation of the preferred embodiment of my invention showing the body member in side view and the track 85 supporting view in section on line 2—2 of Fig. 1.

The supporting member comprises wall attaching flange 5 and the lateral extending body member 6. In the form shown the 90 member 6 is perpendicular to the wall member 5. It is understood that if the wall member 5 be adapted for attachment to the ceiling or roof then the extending body member 6 would have to be arranged 95 at an angle of 90° from the position shown in the drawings. The member 6 is provided with an elongated opening 7 formed by walls 8. The upper edges of the walls 8 are provided with a series of serrations 9, the purpose of which will be explained later. 10 is a track supporting member and consists of a bracket surrounding the track 11 which in this instance is shown as being of the well known trolley track 105 type, it being understood that any other type might be used in which the bracket 11 may be made to conform to the config-

ration of the track so employed. In the upper portion of the bracket 10 I provide a bolt 12 having an enlarged head 13 passing through an aperture 14 and held within the bracket 10 to permit rotative movement thereof on the bolt 12. For locking the bolt 12 against rotative movement in the bracket 10 I employ preferably a lock nut 15 and a washer 16 so that by turning 10 the nut 15 tightly against the washer 16 the bracket 10 will be locked from rotative movement with respect to the bolt 12. The bolt 12 is adapted to extend upwardly through the slot 7 in the body member 6 and is provided at its upper end with a member 16' provided with teeth 17 for engagement with the serrations 9. The member 16' extends across the aperture 7 and is adapted to engage a portion of the 15 serrations 9 on the walls 8. For clamping the bolt 12 in position in the slot 7, I provide a washer 18 adapted to extend across the aperture on its under side and a suitable lock nut 19 and washer 19a. For bearing 20 against the member 16' I provide a nut 20 and a lock washer 21. The wall member 5 is provided with proper apertures 22 to receive bolts, rivets or similar 25 attaching means for securing the same in position on the doorway or like place.

In Fig. 2 I have shown a plate 23 arranged across the end of the bracket 10. This plate is preferably inserted in the end bracket to prevent longitudinal movement 30 of the track when mounted in the brackets 10. I do not claim this plate as a part of my invention but show it merely as one means of preventing travel of the track when once mounted in the brackets.

40 The operation of the device is as follows: The body member is attached to the doorway of any suitable head room by means of bolts or lag screws (not shown) being passed through the apertures 22 in the wall member 5. The bolt 12 is mounted loosely in the slot 7 so as to permit lateral movement of the bolt in the slot, the lock nuts 19 and 20 being loose. Also the lock nut 15 is loose to permit rotative movement of 45 the bracket. The track 11 is then inserted in the brackets and adjusted to proper position with respect to the doorway. This adjustment includes the movement of the bolt 12 in the slot 7 and also rotative movement of the bracket 10. When the track is adjusted the lock nuts 19 and 20 are tightened to bring the member 16' in engagement with the serrations 9 and thus hold the track supporting member 50 positively and securely against any bodily movement thereof. The lock nut 15 is then tightened against the washer 16 which locks the bracket 10 against rotative movement 55 on the bolt 12. If desired the bracket 10 may be entirely removed from the member

6 and applied to the track at some convenient place and then slid along the track so as to register with the slots 7 in the brackets when applied thereto.

It is, of course, understood that modifications of such a device are possible and such modifications as come within the scope of the appended claims I consider as coming within the spirit of my invention.

75 I claim:

1. A bracket comprising a wall attaching member, a body member and a load supporting member, the latter being rotatably and bodily movably associated with said body member, and means for securing said parts 80 in a plurality of adjusted positions, substantially as described.

2. A bracket comprising a wall attaching member, a body member and a load supporting member, the body member being provided with an elongated portion, the load member being provided with a member for coöperating with said elongated portion, and clamping means on the coöperating member for adjustably engaging said elongated portion, substantially as described.

3. A bracket comprising a wall attaching member, a body member and a load supporting member, the body member having an elongated slot, a bolt on the load member for coöperation with the slot, clamping means carried by the bolt and adapted to secure said bolt in adjusted position in the slot, substantially as described.

4. A bracket comprising a wall attaching member, a body member and a load supporting member, the body member having an elongated slot, a bolt on the load member for coöperation with the slot, clamping means carried by the bolt and adapted to secure 100 said bolt in adjusted position in the slot and a pivotal connection between the load member and the bolt, substantially as described.

5. A bracket comprising a wall attaching member, a body member and a load supporting member, the body member having an elongated slot, a bolt on the load member for coöperation with the slot, clamping means carried by the bolt and adapted to secure 110 said bolt in adjusted position in the slot, a pivotal connection between the load member and the bolt, and means for locking the load member in adjusted rotative position with respect to the bolt, substantially as described.

6. A bracket comprising a wall attaching member, a body member and a load supporting member, the body member having an elongated slot, a bolt on the load member for coöperation with the slot, clamping means carried by the bolt and adapted to secure 120 said bolt in adjusted position in the slot, a pivotal connection between the load member and the bolt, means for locking the load member in adjusted rotative position with respect to the bolt, the body member pro- 125

130

vided with an elongated slot having serrated edges, a member on the bolt for engaging said serrated edges and means carried by the bolt for clamping said engaging means with 5 said serrated edges, substantially as described.

7. A bracket for adjustably supporting tracks comprising a wall attaching member, a body member and a track supporting member, the body member being provided with 10 an elongated slot, the upper edges of the slot being provided with serrations, a bolt on the track supporting member adapted to extend through said slot, means on said bolt 15 adapted for coöperation with said serrations, and means for moving said clamping means into tight engagement with said serrations, substantially as described.

8. A bracket for adjustably supporting 20 tracks comprising a wall attaching member, a body member and a track supporting member, the body member being provided with an elongated slot, the upper edges of the slot being provided with serrations, a bolt 25 on the track supporting member adapted for coöperation with said serrations, means for moving said clamping means into tight engagement with said serrations, and means carried by the bolt for engaging the under 30 side of the body member whereby to clamp the bolt firmly in adjusted position with respect to said body member, substantially as described.

9. In a device of the class described, the 35 combination of an attaching portion, a body

portion and a load supporting member, the body portion being provided with a slot having corrugated edges, means on the load member for coöperative engagement with said slot and means carried by the latter 40 means for securing said engaging means in positive engagement therewith, substantially as described.

10. A bracket of the class described in combination, a body member extending outwardly of the wall, a load supporting member, means for fixedly securing said body member to a support, the load member being provided with adjustable means for coöperating with said body member, whereby to 45 position the supported load in any position along the bracket member, substantially as described.

11. A bracket of the class described in combination, a body member, a load supporting member, means for fixedly securing said body member to a support, the body member having an elongated portion, the load member being provided for adjustably coöperating with said elongated portion of the body 50 member, whereby to position the supported load in any position along the bracket member, substantially as described.

Signed at Danville, State of Ills. this 21 day of May A. D. 1917.

ROY B. OLDER.
